UNITED STATES PATENT OFFICE

WILLIAM WELLER, OF WISCONSIN RAPIDS, WISCONSIN

SMOKER'S PIPE

Application filed February 11, 1931. Serial No. 515,103.

This invention relates to smokers' pipes, more particularly to an attachment for the pipe stem and has for its object to provide, in a manner as hereinafter set forth, the stem of the pipe with means to provide for a cool, clean, dry and non-injurious smoke when the pipe is used.

A further object of the invention is to provide, in a manner as hereinafter set forth, a 10 smoker's pipe with means in the form of a trapping device for the saliva and nicotine resulting in a cool, clean, dry and non-injurious smoke when the pipe is used.

A further object of the invention is to provide, in a manner as hereinafter set forth, a 15 smoker's pipe with means for absorbing the saliva and whereby the warm air circulating through the pipe will act to evaporate the saliva.

A further object of the invention is to provide, in a manner as hereinafter set forth, a 20 smoker's pipe with means to provide a cool, clean, dry and non-injurious smoke and with such means so constructed and arranged to overcome the use of pipe cleaners.

A further object of the invention is to provide, in a manner as hereinafter set forth, a 25 smoker's pipe provided with means to prevent the bottom of the pipe bowl becoming moist.

A further object of the invention is to provide, in a manner as hereinafter set forth, a 30 smoke conducting attachment for a smoker's pipe opening at its inner end into the bottom of the bowl of the pipe and so constructed and arranged as to provide for expeditiously opening its point of communication with the bowl should such point become clogged.

A further object of the invention is to provide, in a manner as hereinafter set forth, a 35 smoke conducting attachment for the stem of a smoker's pipe and with such attachment so constructed and arranged to provide for the expeditious removal of any ash lodged therein.

Further objects of the invention are to provide, in a manner as hereinafter set forth, an attachment for the stem of a smoker's pipe for the purpose referred to and which is simple in its construction and arrangement,

strong, durable, compact, thoroughly efficient in its use, readily installed with respect to a pipe and inexpensive to manufacture.

With the foregoing and other objects in view, the invention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:—

Figure 1 is a longitudinal sectional view of a pipe showing the adaptation therewith of a stem attachment in accordance with this invention.

Figure 2 is a top plan partly in section.

Figure 3 is a section on line 3—3 Figure 1.

Figure 4 is a section on line 4—4 Figure 1.

Figure 5 is a section on line 5—5 Figure 1.

Referring to the drawings in detail, 1 denotes the bowl, 2 the stem and 3 the mouth piece of a smoker's pipe. The bowl 1 at one side of its bottom is formed with a circular opening 4. The diameter of opening 4 is the same as the inner diameter of the stem at the point of joiner of the latter with the bowl. The mouth piece at its forward end is provided with a socket 5.

Positioned within the opening 4, flush with the inner face of the bowl, and also extending through stem 2 and into the socket 5 of the mouth piece 3 is a combined trapping, smoke conducting and coupling element 6.

The element 6 includes a forward part 7, an intermediate part 8 and a rear part 9. The parts 7 and 9 are of circular cross section and the part 8 of substantially oval shape cross section. The parts 7 and 8 do not tightly engage with the inner face of the stem 2. The outer diameter of part 9 is slightly greater than that of part 7 and the width of part 8. The part 9 constitutes a coupling portion and which frictionally engages with the inner face of stem 2 at the rear portion thereof and is also secured to the wall of the socket 5.

This arrangement provides for connecting the element 6 to the stem 2 at but one point, rather than throughout the stem, and under such conditions the attachment can be readily removed from stem 2 when occasion requires.

The part 7 has its forward face flush with the wall of bowl 1 and such face is dished, as at 10 to form a continuation of the curvature of the bottom of the bowl. That is to say the bottom of the wall of the bowl. The part 7 axially thereof is formed with a port 11 which opens into the bowl 1 at the bottom thereof. The part 7 has the rear of its top 15 cut away to reduce the outer diameter of the rear portion 12 of the part 7. The top of the rear portion 12 of the part 7 is oppositely beveled as at 13. The part 7 is formed with a passage extending from a point centrally of the bottom of such part to the top of the reduced portion 12 of part 7. The passage is indicated at 14 and inclines rearwardly from its lower to its upper end. The lower end of the passage 14 is closed by the stem 2. The 20 upper end of passage 14 is open. The rear end of port 11 opens into the passage 14 centrally thereof.

The height of part 8 is less than the height of parts 7 and 9 and part 8 is disposed substantially centrally with respect to parts 7 30 and 9. The part 8 at its forward end terminates at the rear end of part 7 and at its rear end terminates at the forward end of part 9. The part 8 is formed with a lengthwise extending slot 15. The outer sides of part 8 abut against opposed sides of the inner face of stem 2. The top and bottom of part 8 are spaced from the top and bottom of the inner face of stem 2.

The part 9 has the lower portion of its top 40 cut away to reduce the outer diameter of the forward portion 16 of said part 9. The top of the forward portion 16 of the part 9 is oppositely beveled as at 17. The bottom of the forward portion 16 of part 9 is also cut away as at 18 to space the part of such forward portion 16 from the bottom of the inner face of the stem 2. The forward portion 16 of part 9 is provided with an opening 19 which gradually decreases in diameter from its lower to its upper end. A portion of the lower end of the opening 19 is closed by the bottom of the inner face of the stem 2. In cross section the rear wall of the opening 19 50 is vertical and the forward wall inclines from its lower to its upper end in a direction towards the rear wall. The upper end of opening 19 is spaced from the inner face of the stem 2 whereby such inner end is permanently open. A portion of the lower end of the opening 19 is permanently open. The part 9 axially thereof is formed with a smoke conducting channel 20 which opens at its forward end into the opening 19 and at its 60

rear end registers with the port 21 formed in the stem 3.

Extending through slot 15 is an absorbing element 22 which functions to absorb the saliva and trap the nicotine. The element 22 extends from the bottom to the top of the inner face of the stem 2. The element 22 is compressible and is rigidly maintained in position by the walls of the slot 15. The height of the element 22 is materially greater than the height of the part 8 of the element 6. 75

The manner of setting up the element 6 provides for the smoke to take a tortuous passage as it passes from the bowl 1 to the channel 20 and from channel 20 into the port or bore of the mouth piece. The smoke also passes through the element 22 and enters the opening 19 either from the top or bottom thereof and from such opening 19 passes into the channel 20. 80

If any ash is collected in the element 6 it is stored within the passage 14 and element 6 can be quickly removed from the stem 2 and the ash eliminated from element 6. If port 11 should become clogged in any manner by the tobacco, by turning the attachment the tobacco will be immediately dislodged and the port opened. The arrangement of the attachment with the element 22 enables the circulation of warm air to evaporate the 90 saliva absorbed by element 22. 95

Occasionally water can be run through the pipe from a faucet or the pipe can be rinsed in water and wipe off the stem only, even though element 22 being soaked with water, 100 the pipe when smoked gives a nice fresh and cool smoke, the water evaporating while smoking the pipe.

What I claim is:—

1. In a smoker's pipe, a combined trapping, 105 smoke conducting and coupling device for mounting in the stem and for extension into the mouth piece of the pipe, said device including a forward part for registering with the inner face of the bowl of the pipe, a rear part for coupling it to the stem and for coupling the latter to the mouth piece and an intermediate part of less height than and coupling said other parts together, said forward part formed with a passage open at one end and closed at its other end by the stem and a port opening at one end into the bowl of the pipe and at its other end into said passage, and said rear part formed with an opening having its ends spaced from the stem and a channel communicating at one end with said opening and at its other end opening into the port or bore of the mouth piece. 110 115 120

2. In a smoker's pipe, a combined trapping, 125 smoke conducting and coupling device for mounting in the stem and for extension into the mouth piece of the pipe, said device including a forward part for registering with the inner face of the bowl of the pipe, a rear

part for coupling it to the stem and for coupling the latter to the mouth piece and an intermediate part of less height than and coupling said other parts together, said forward part formed with a passage open at one end and closed at its other end by the stem and a port opening at one end into the bowl of the pipe and at its other end into said passage, said rear part formed with an opening having its ends spaced from the stem and a channel communicating at one end with said opening and at its other end opening into the port or bore of the mouth piece, said intermediate part having a lengthwise extending slot, and an absorbent element connected to said intermediate part by the walls of said slot and bearing against opposed portions of the inner face of the stem.

20 In testimony whereof, I affix my signature hereto.

WILLIAM WELLER.
